UNITED STATES PATENT OFFICE.

WALTER G. BENNETT AND JOHN F. SEYFANG, OF TOLEDO, OHIO.

MACHINE FOR MOLDING CONCRETE BLOCKS.

No. 810,025.

Specification of Letters Patent.

Patented Jan. 16, 1906.

Application filed August 3, 1905. Serial No. 272,522.

To all whom it may concern:

Be it known that we, WALTER G. BENNETT and JOHN F. SEYFANG, citizens of the United States, and residents of Toledo, in the county of Lucas and State of Ohio, have invented a new and useful Improvement in Machines for Molding Concrete Blocks, of which the following is a specification.

Our invention relates to a machine for molding building-blocks, and has for its object to produce a molding-machine for the purpose that is adapted to conveniently and expeditiously mold cement concrete into various forms of blocks required for the construction of the walls of buildings and other purposes.

A further object is to provide a machine of the kind that is adapted to mold hollow blocks that are adapted when laid up in a wall to form continuous air-spaces in the wall.

We accomplish these objects by constructing a molding-machine as hereinafter described and illustrated in the drawings, in which—

Figure 1 is a perspective view of a molding-machine constructed in accordance with our invention and showing the cores and the hinged sides and ends of a bonding-chimney-block mold in open position on the molding-table. Fig. 2 is a top plan view of the molding-table with the chimney-block mold in closed position thereon. Fig. 3 is a vertical section of the machine on line X X of Fig. 2, showing the flue-core elevated. Fig. 4 is a similar section on line y y of Fig. 2, showing all the cores lowered and the paving-block mold-frame elevated and a paving-block molded therein. Fig. 5 shows a mold for a column-section. Fig. 6 is a top plan view of a mold for a hollow wall-block, and Fig. 7 shows a section of a water-table or coping-block mold with the molded block therein.

In the drawings, 1 represents a rectangular box-shaped table-top, having integral therewith around its sides and ends flush with their bottom edges an outwardly-extending base flange or ledge 2. The top 1 is suitably mounted and supported on the end frames 3, comprising the legs 4 and cross-bars 5 and 6, and the frames are cross-connected and braced by the spiders 7 and 8, which are

bolted to the legs one above the other to form a solid and substantial support for the table-top and for the attachment and support of the guides and bearings of the mechanism for projecting and withdrawing the cores of the molds.

The cross-bars 6 are provided with alined bearings 9, near the front legs of the side frames, in which is mounted a rock-shaft 10, which has end portions projecting outside the bearings, on which are mounted the toothed segments 11 and at suitable intervals between the bearings the toothed segments 12 and 13. Each segment is provided with a set-screw 14, by which it may be secured against turning on the shaft. There is also mounted on one projecting end of the rock-shaft the operating-lever 15, which has pivoted to its central portion a ratchet-pawl 16, which is adapted to engage incuts 17 in an arc-bar 18, suitably located and secured to the adjacent end frame. The ratchet-pawl 16 is connected by a rod 19 to a spring-resistant hand-grasp lever 20, pivoted to the handle portion 21 of the lever 15 and adapted to be jointly grasped therewith and to automatically engage the ratchet-pawl with the incuts of the arc-bar when released and to disengage it therefrom when drawn toward the handle 21.

The segments 11 intermesh with rack-bars 22, which are mounted vertical in upper guide-bearings 23 and lower guide-bearings 24, formed, respectively, in lugs 25 and 26 of the upper and lower cross-bars 7 and 8, and to the upper ends of the rack-bars 22 is secured a box-mold frame 27, adapted to telescopically receive the sides and ends of the table-top 1 and to rest in a lowered position on the ledge 2 thereof.

The toothed segment 12 intermeshes with a rack-bar 28, integral with an angle-plate 29, having opposite side members 30 extending in opposite directions at right angles to the central member. Opposite each side member 30 and in engagement therewith is provided the rectangular core-bars 32 and 33, which are mounted vertical in guide-incuts 32^a and 33^a, formed, respectively, in the spiders 7 and 8 in alinement and adapted to guide vertical movement of the bars. The bars 32 and 33 are each provided with a lon-

itudinal slot 34, through which extends a bolt 35, the threaded end of which also extends through a bolt-hole in the adjacent side member 30 of the angle-plate 29 and is provided with a thumb-nut 36, by which the core-bar is secured to the side member. On the top ends of the core-bars 32 and 33 are respectively centrally secured the elongated ventilator-core 37 and the cylindrical flue-core 38, which are together used in forming a bonding chimney-block. The elongated core may also be separately used in molds for elongated wall-blocks, and the cylindrical core may also be separately used with a special cylindrical mold for forming porch-column sections.

The toothed quadrant 13 is of increased radius and intermeshes with a rack-bar 39, which extends vertically through suitable aligned guide-openings in the spiders 7 and 8, and in the top end of the rack-bar 39 is centrally secured a cylindrical core 40 of reduced diameter, that is adapted for use in forming porch-column sections of reduced diameters.

The table-top 1 is provided with suitable openings for the projection of each of the cores 37, 38, and 40 through the table-top. The cores are of equal height, and when fully projected they are adapted to form openings through blocks of the maximum thickness. The cores 37 and 38 may be either separately or simultaneously projected by the operating-lever 15, the set-screw of the segment 12 being tightened on the rock-shaft, according as the thumb-nuts 36 of the bolts 35 are tightened or loosened to compress the bolts on the side members 30 and the core-bars 32 and 33, respectively.

The operating-lever 15 is so mounted on the rock-shaft relative to the segments that when the cores are all below the table-top the lever is in a horizontal position, and when raised upward from that position slightly more than ninety degrees of the arc of its movement it will fully project the cores 37 and 38 through the table-top, and the arc-bar 16 is provided with an incut 17 to receive the ratchet-pawl at a point which adapts the pawl to hold the cores fully projected, and between this upper incut and the lower limit of the movement of the lever incuts 17 are provided in the arc-bars at such intervals as will establish the projection of the cores for blocks of different fractional thicknesses of the maximum thickness.

The radius of the segment 13 being proportionately longer than the radius of the segment 12, the full projection of its core is effected by a throw of the lever which is adapted to engage the pawl with a certain one of the intermediate incuts 17. The segments 11 being of the same radius as segment 12, the mold-frame 27 is projected the same distances

above the table-top as the cores 37 and 38, when the ratchet-pawl is in engagement with any one of the intermediate incuts 17.

To form wall-blocks of the different shapes and dimensions required in the construction of the walls of a building, there is provided a special form of hinged mold-box for each special form of block and for each thickness of each form.

The special forms of mold-boxes required in ordinary construction are the main wall-block mold 41^a, the water-table or coping-block mold 41^b, and the bonding-chimney-block mold 41^c. The main wall-block mold 41^a comprises a rectangular plate 42, forming the rear sides of the mold, the end plates 43, hinged to the plate 42 and adapted to abut the ends of the plate and form therewith right-angle corners, and a front side plate 44, adapted to abut the free ends of the end plates 43 and form therewith right-angle corners of the box. The box thus formed is secured together by hook-latches 45, pivotally secured to the ends of the side 44 and engaging latch studs or staples 46 of the end plates. The end plates are provided on their inner faces with half-cylindrical core-blocks 47, arranged to be in line with the core 37 when the mold-box is placed on the table-top, and to insure and facilitate the mold-box being properly located around the core the bottom edge face of the plate 42 is provided with projecting dowel-pins 48, adapted to enter holes in the table-top suitably located and adapted to receive them.

Before attaching the front side plate a pallet having dimensions adapting it to fit between the sides and ends of the mold-box as a bottom therefor and provided with an opening adapted to register with the opening in the table-top for the core 37 is placed in position registering the openings, and the front plate 44 being then attached and the lever raised to project the core through the pallet and the box the mold is ready to receive the concrete mixture, and being filled therewith and the concrete being tamped therein and the surplus being struck off even with the top of the mold the block is completed.

To remove the block, the front plate of the mold is unlatched and removed, and the end plates are swung back on their hinges. The block may then be carried on the pallet to a place of storage, and the block and pallet being inverted and deposited the pallet may be removed for use in forming another block. The blocks formed in the mold 41^a have a central elongated opening 50 and at the ends semicylindrical cavities 51 in line longitudinally of the block with the central opening, as shown in Fig. 6, and the blocks thus formed and laid up end to end in bonding courses form continuous air-spaces extend-

ing from bottom to top of the wall, with the central openings of the blocks of each course connected by the cylindrical openings formed by the cavities of the joined ends of the 5 blocks of the next course with the central openings of the blocks of the third course, and so on throughout the entire wall.

The core-blocks 47 are detachably secured to the end plates of the mold-box 41^a by a 10 screw 52, and for forming the corner-blocks of each wall-course one of the core-blocks 47 is removed from the mold-box.

To form blocks for a water-table or coping, a special mold-box 41^b, constructed, as shown 15 in Fig. 7, to form a projecting table 53, is used in conjunction with the core 37. For this form of block a detachable front side plate 44^b has its lower portion adapted to form the under side and outer edge of the 20 water-table, and the lower portions of the abutting ends of the hinged end plates are extended to conform therewith. To form the upper bevel of the water-table, the pallet 49^b is provided with a bevel 54. Otherwise 25 the mold-box 41^b is constructed similar to the mold-box 41^a, and the end plates are each provided with a core-block 47 for all the blocks of the water-table course except the end blocks, in which one core-block 47 is 30 omitted, according as the block is to be used at the right or left end of the course, and it is manifest that if the water-table course is to be extended around the corner that only a slight modification of the front and one end 35 plate of the mold-box and of the pallet is required to extend the water-table along the end as well as along the side of the block.

To form a bonding chimney-block that is adapted to be run in courses with the wall-blocks described, we employ a mold-box 41^c, in conjunction with which is used, as shown in Figs. 1 and 2, the cores 37^a and 38. This mold-box is rectangular and comprises the rear plate 55, to which is hinged at one end 40 the end plate 56 of equal dimensions and to the opposite end the angled end plate 57, which is also of equal dimensions with plate 56 and is bent central of its length at a right angle in a direction away from the plate 56, 45 the plate 58, which is one-half the length of the plate 57 and is hinged to the free end of the plate 57, and a detachable side plate 59. The plates 56 and 57 are hinged to abut the ends of the rear plate 55 at right angles. The 50 plate 58 is hinged to the outer end of the plate 57 at a right angle, and the plate 59 is of a length to abut the free ends of the plates 56 and 58 at right angles to each when the plates 56, 57, and 58 are at right angles and abut- 55 ting the plates to which they are hinged. The ends of the plate 59 are provided with hooks 60, which are adapted, respectively, to engage studs 61, projecting from the outer

faces of the plates 56 and 58 and lock the parts together.

The mold-box thus constructed is adapted in its dimensions to form a rectangular chimney-block of uniform thickness with the wall-block and slightly more than twice the length of the wall-block on the outer face, and which for three-fourths of its length has double the width of the wall-block and for the remaining one-fourth is of equal width with the wall-block, forming a bonding extension 62 from the main body portion 63 of the block, the 65 extension being one-half the length of a wall-block and of equal width and thickness, whereby the chimney-block may be laid in courses and bonded with the wall-blocks by inverting the chimney-blocks of alternate 70 courses and registering the flue-openings formed by the core 38.

To form bonding chimney-blocks, the mold-box 41 is located on the table-top in proper position around the core-openings by 85 dowel-pins 64, projecting from the bottom face of the plate 55 and set into suitable holes in the table-top, and the walls of the box are closed around a pallet 65, fitting the mold as a bottom and having core-openings registered 90 with the openings in the table-top for the cores 37 and 38. Preferably, however, a core 37^a of reduced width is substituted for the core 37, as shown in Fig. 1, and the opening in the pallet to receive it is also proportionately reduced.

To arrange the machine for molding the bonding chimney-block, the side members of the rack-plate 29 are secured to the core-bars 32 and 33, respectively, by tightening 100 the nuts 36 on the bolts 35. The segment 12 is tightened on the rock-shaft 10 by its set-screw and the set-screws of segments 11 and 13 are loosened. The cores 37^a and 38 are then fully projected by the lever and locked 105 in such position by the pawl 16. The operations of molding, withdrawing the cores, opening the mold-box, and removing the block is the same as described for a wall-block.

For molding sections of a porch-column cylindrical molds 41^d of diameters suitable to either of the cores 38 and 40 are employed. These molds are constructed, as shown in Fig. 5, of longitudinal half-sections 66, hinged 115 to abut and form a complete cylinder and to open for the removal of the section. One section 66 is provided with dowel-pins and the table-top with holes to receive them and adapted to locate the mold concentric to the core-opening. For this mold an annular pallet having a central opening registering with the core-opening in the table-top and fitting the bottom of the mold when closed around it may be used or omitted, as desired.

The machine being arranged to project the

core suited to the diameter of the mold used, the operations of projecting the core, molding, and removing the molded section are the same as before described for other forms of blocks.

For molding paving-blocks all the segments excepting segment 11 are loosened on the shaft 10, and the lever is raised to elevate the mold-frame 27, so as to project the sides 10 of the frame above the table-top the distance required for the thickness of the block and the pallet 67, on which it is molded and by which it is removed, as shown in Fig. 4. When the mold thus formed is filled, tamped, 15 and struck off, the lever is released and lowered, thereby lowering the frame to its normal position, which permits of the removal of the pallet and block from the table-top.

It is manifest that by providing the pallet 20 67 with a central core of the desired form and dimensions, either rectangular or cylindrical, there can be readily molded in the frame 27 tops for catch-basins and the like or that by providing the pallet with subdividing partition-strips slabs of various lengths, thickness, and widths may be readily and expeditiously formed within the frame as a mold. It is obvious, also, that either the back or the front plate of the hinged mold 41^a may be 25 adapted on its inner face to produce a "rock-face" finish on the outer wall of the wall-blocks and also that by providing a hinged mold having those plates curved to the arc of a required circle wall-blocks for towers, 30 bay-windows, and the like running uniform with wall-blocks molded in the mold 41^a may be readily produced.

It will thus be seen that we have produced a machine that, in combination with a variety 40 of hinged molds, is adapted to facilitate the molding of the different-shaped blocks entering into the construction of a building, as well as blocks for other purposes.

What we claim to be new is—

45 1. In a machine for molding concrete blocks, the combination with a mold-table having openings for the projection of cores above the table from beneath, of cores for the openings, an articulated mold adapted 50 to surround one or more of the core-openings, means to project the cores singly or collectively through their respective openings into the mold, and to withdraw them therefrom, substantially as set forth.

55 2. In a machine for molding building-blocks, the combination of a support, a table provided with core-openings, mounted on the support, a core for each opening, means to jointly or severally project the cores different 60 distances through their respective table-openings, and withdraw them therefrom, means to support the cores at different distances of projection through and above the

table, and a plurality of articulated mold-boxes severally adapted either to individual 65 or to collective use of the cores therein for the formation of complementary hollow structural blocks, substantially as set forth.

3. The herein-described molding-machine comprising a support, a mold-table mounted 70 on the support, and provided with core-openings, a core for each opening, an upwardly and downwardly movable mold-frame surrounding the table, a rock-shaft journaled on the support, toothed segments 75 mounted on the shaft, each adapted to be tightened or loosened thereon, stems for the cores and the mold-frame, each movable upwardly and downwardly in guides of the support, racks for the stems intermeshing with 80 the segments, and adapted to move the stems as moved by the segments, a lever for the rock-shaft adapted to rock the segments jointly or severally as tightened on the shaft and thereby move the racks to severally or 85 collectively project or withdraw the cores and the mold-frame, means to lock the lever at different distances of its movement and support the cores or the mold-frame at different elevations, and articulated molds adapted 90 to be located on the table around the core-openings, substantially as set forth.

4. In a machine for molding concrete blocks, the combination with a box table-top mounted on a support, of a mold-frame telescopically mounted around the table-top and movable upwardly to raise portions of its sides and ends above the level of the table-top and form therewith a mold-box, and downwardly to withdraw the frame, means 95 100 to raise and lower the mold-frame, means to support the mold-frame at different distances of its movement and a movable pallet mounted on the table-top and fitting the raised portions of the sides and ends of the 105 mold-frame as a bottom.

5. In a machine for molding hollow wall-blocks, the combination with a table-top provided with core-openings, a movable core for each opening, and mechanism for projecting the cores through their respective openings singly or collectively, of a plurality of mold-boxes respectively adapted to receive one or more of the cores and to form therewith complementary wall-blocks of different 110 115 forms for the same or different courses, said mold-boxes comprising end plates hinged to the ends of one side plate, one removable side plate, and a half-core for one or both the end plates, adapted to form halves of joint-openings adapted to connect the central core-openings of blocks above and below the joint, substantially as set forth.

6. In a machine for molding concrete wall-blocks, the combination with a table-top 120 125 provided with one elongated and one cylind-

drical core-opening, a movable core for each opening, and mechanism for jointly or severally projecting the cores through their respective openings, of two hinged mold-boxes
5 one adapted to receive therein the elongated core and form therewith a hollow wall-block having half-joint openings, and the other to receive both the elongated and cylindrical core and form therewith a chimney-block
10 having an extension adapted to bond with the wall-block, substantially as set forth.

In witness whereof we have hereunto signed our names, in the presence of two subscribing witnesses, this 25th day of July, 1905, at Toledo, in the county of Lucas and 15 State of Ohio.
